ELECTROMAGNETIC BELL

Joseph F. Ebert, Hollis, N. Y., assignor to Signal
Engineering & Manufacturing Company, New
York, N. Y., a corporation of Massachusetts

Application June 18, 1931, Serial No. 545,355

1 Claim. (Cl. 177—7)

The present invention relates to electromagnetic bells of the single stroke type in which the energization of an operating solenoid causes a plunger or striker to hit a gong disposed in the path of movement of the upper end of the plunger, the plunger remaining in its striking position as long as the solenoid is energized.

The object of the invention is to provide an improved attachment for bells of the above indicated type whereby the bell may be readily converted into a recurrent stroke or vibrating bell, that is a bell in which the plunger will make separate strokes, uniformly spaced, as long as the solenoid remains energized. The attachment which constitutes the present invention consists of an improved circuit making and breaking device adapted to cooperate with the bell plunger, all of the parts being adapted to be applied to the magnetic frame of the bell as an assembly, as will hereinafter appear from the following description with reference to the accompanying drawing, in which:—

Fig. 1 is a transverse sectional view of an electromagnetic bell provided with a circuit controlling attachment embodying the invention.

Fig. 2 is a rear elevation of the magnetic frame of the bell with the circuit controlling attachment secured thereto.

Fig. 3 is a plan view of the attachment shown in Fig. 2, removed from the bell.

Fig. 4 is a fragmentary sectional view showing a portion of the parts of Fig. 1 in a different position and on an enlarged scale.

Like reference characters refer to like parts in the different figures.

Referring to the drawing, the bell structure to which my improved circuit controlling attachment is applied consists of a magnetic yoke or frame 1 providing a recess 2, in which is received an operating solenoid 3. The solenoid 3 surrounds a tube 4 of insulating material received in aligned openings 5 provided in the frame 1, and a striker or plunger 6 is longitudinally movable in the tube 4 under the influence of the solenoid 3.

Preferably the lower end of the tube 4 is closed by a suitable plug 7, so as to maintain the plunger 6 in the position shown, with only the upper portion of the plunger extending within the solenoid, then assumed to be in a deenergized condition.

A resonant gong 8 of any desired type is secured to the magnetic frame 1 by a bolt 9, the open rim of the gong 8 extending over the axis of the magnetic plunger 6. Consequently, when the solenoid 3 is energized from any suitable source of electrical energy, the plunger 6 will be drawn

up within the solenoid 3, and a metal striking tip 10 at its upper end will hit the rim of the gong a single sharp blow. The plunger 6 will remain in its striking position as long as the solenoid 3 is continuously energized, and the object of the present invention is to provide an attachment for a single stroke bell construction of the type above described, whereby the bell plunger is adapted to hit recurrent strokes on the gong 8 in response to continuous energization of the solenoid 3.

The attachment consists of a U-shaped bracket 11, the spaced legs of which provide flanges 12, 12 that are attached to the face of the magnetic frame 1 surrounding the coil recess 2 by means of screws 13 so that the bracket may be readily attached to or removed from the frame. As best shown in Fig. 1, the lower portion of the bracket 11 carries a series of plates 14 of insulating material between which are clamped a pair of upwardly extending resilient contact fingers 15 and 16, screws 17 serving to secure the assembled insulating plates 14 and contact fingers 15 and 16 to the bracket 11, with finger 15 extending beyond finger 16.

In assembling the contact fingers 15 and 16, the finger 16 is initially bent away from the finger 15 so as to yieldingly maintain contact tips 15a and 16a, respectively, carried by the fingers, in engagement. Consequently, the contact finger 15 is slightly deflected out of exact parallelism with a stiff stop arm 18 extending between the fingers. The upper end of the arm 18 provides an opening 19 see Fig. 4, through which the engaged contact tips 15a and 16a freely extend, so that both fingers 15 and 16 are adapted to be flexed independently of the arm 18, as will hereinafter appear.

One terminal of the solenoid 3 is connected to the contact finger 15 by means of a lead 20, while the other terminal thereof is connected to a terminal screw 21 provided by an insulating block 22 located in a junction box 23 of any desired type, upon which the bell frame 1 is mounted. A second terminal screw 24 is connected by a lead 25 to the other contact arm 16, so that with the contact tips 15a and 16a in engagement, the circuit between the solenoid 3 and the terminal screws 21 and 24 is complete. Consequently, energization of the terminal screws 21 and 24 in the junction box 23 from any suitable source of electrical energy, not shown, will cause energization of the solenoid 3.

As the plunger 6 is drawn upwardly within the solenoid 3 in response to energization thereof, one arm 26a of a lever pivoted at 27 is engaged

5 by the plunger 6 to turn the lever and move its other arm 26b into engagement with the upper end of the contact finger 15 which extends above the other finger 16. Preferably the pivot 21 for the lever is supported between spaced ears 28 provided by the bracket 11, so that the lever forms part of the bracket assembly. The lower end of the lever arm 26b carries an insulating tip 29 for engagement with the contact finger 15, and as 10 best shown in Fig. 3, the outer end of the other lever arm 26a provides an open notch 30 adapted to freely receive the striking tip 10 of the plunger. With this arrangement, the tip 10 passes through the notch 30 on its upward movement and the 15 lever arm 26a is not turned until it is engaged by the shoulder 6a of the plunger 6 just below the tip 10.

It is evident from a consideration of Fig. 1 that the shoulder 6a of the plunger 6 will engage the 20 lever arm 26a before the tip 10 strikes the gong 8, thereby turning the lever to cause the arm 26b to engage contact finger 15. As the finger 15 moves away from the stiff stop arm 18, the other finger 16 follows it until a washer 31 carried by the 25 finger 16 engages the arm 18. The washer 31 is of greater diameter than the opening 19 in the arm 18, so that movement of the contact tip 16a is checked just as continued flexure of the finger 15 by the lever arm 26b separates the contact tip 30 15a therefrom, as shown in Fig. 4.

Due to the fact that engagement between the contact tips 15a and 16a is momentarily maintained after the finger 15 starts to move, the inertia of the upwardly moving plunger 6 causes it 35 to complete its upward movement to strike the gong 8 a sharp blow just as the solenoid 3 is deenergized by separation of the contact tips 15a and 16a. As the plunger 6 drops upon deenergization of the solenoid 3, the lever arm 26b releases 40 the deflected finger 15, whereupon the tip 15a reengages the tip 16a to reestablish the circuit of the solenoid 3. This reengagement of the tips 15a and 16a is accompanied by a yielding of the finger 16 under the pressure of the finger 15, thereby 45 by effectively preventing any rebound between the contact tips which might otherwise occur, were one of the fingers rigid.

Owing to the fact that the tip 15a reengages the tip 16a before the lever arm 26b has actually released the end of the finger 15, the circuit of the solenoid 3 is reestablished slightly in advance of the arrival of the falling plunger 6 at the bottom of the tube 4, as shown in Fig. 1. Therefore, the magnetic frame is fully saturated by the time the 55 plunger 6 reaches its lowest position, with the result that the plunger starts on another stroke without any appreciable time lag. Furthermore, the energization of the solenoid in advance of the arrival of the plunger to its lowermost position 60 serves to cushion the downward movement of the

plunger. This insertion has been made to indicate in the disclosure an advantage of applicant's bell upon which claim was held allowable. On the next upward stroke of the plunger 6, the operation is the same, the circuit of the solenoid 3 5 being maintained through the yielding fingers 15 and 16 up to the point where the tip 10 is just about to strike the gong 8.

As a result of the above described functioning of the circuit controlling device, the bell is adapted 10 to strike recurrent strokes on the gong 8 as long as the terminal screws 21 and 24 are energized, the strokes being clear and distinct, with uniform intervals therebetween. The simultaneous movement of both fingers 15 and 16 in response to turning of the lever arm 26b insures that the circuit of the solenoid will be maintained up to the striking of the gong and will be reestablished before the plunger has fallen all the way. This insures not only uniform timing of the signals, but also 20 prevents the plunger from striking the gong lightly, or missing altogether, due to breaking the solenoid circuit prematurely. In other words, the tendency of the yieldable fingers 15 and 16 to maintain the solenoid circuit during flexure of 25 the finger 16 by the lever arm 26b renders the timing of the device more uniform, in comparison with a circuit controlling device employing the usual fixed and movable contacts.

30

I claim:

In an electromagnetic bell, the combination with a magnetic frame carrying a solenoid, a magnetic plunger movable axially of the solenoid and a gong carried by said frame with its open rim extending in the path of movement of said plunger, 35 of a circuit making and breaking device for controlling the energization of said solenoid comprising a pair of yieldable contacts normally in engagement to maintain the circuit of said solenoid, with one of said contacts initially deflected, 40 a rigid stop interposed between said contacts out of engagement therewith, and an actuating member responsive to movement of said plunger towards said gong for engaging the undeflected contact before said plunger strikes the gong and moving it away from the deflected contact, the initially deflected contact following the movement of the other contact by said actuating member to maintain the circuit of said solenoid until said contact strikes said stop, after which further 50 movement of the other contact by the actuating member serves to break the circuit of the solenoid just as said plunger strikes the gong, downward movement of said plunger following deenergization of the solenoid permitting re-engagement of 55 said contacts, free of said stop, to re-energize said solenoid in advance of the arrival of said plunger in its lowermost position.

JOSEPH F. EBERT. 60

CERTIFICATE OF CORRECTION.

Patent No. 2,099,929.

November 23, 1937.

JOSEPH F. EBERT.

It is hereby certified that error appears in the printed specification of the above numbered patent requiring correction as follows: Page 2, second column, lines 1, 2 and 3, strike out the words and period "This insertion has been made to indicate in the disclosure an advantage of applicant's bell upon which claim was held allowable."; and that the said Letters Patent should be read with this correction therein that the same may conform to the record of the case in the Patent Office.

Signed and sealed this 1st day of February, A. D. 1938.

Henry Van Arsdale,
Acting Commissioner of Patents.
